BICYCLE CARRIER FOR AUTOMOBILES

Shigeto S. Shiota, 2686 Cordelia Road,
Los Angeles, Calif. 90049

Filed Nov. 12, 1971, Ser. No. 198,492

Term of patent 14 years

Int. Cl. D12—16

U.S. Cl. D12—158

FIG. 1 is a perspective view of a bicycle carrier for automobiles embodying my new design.

FIG. 2 is a top plan view thereof.

FIG. 3 is a rear elevational view thereof.

FIG. 4 is a side elevational view thereof.

FIG. 5 is a bottom plan view thereof.

The broken lines shown in FIGS. 1 and 4 are for illustrative purposes only.

I claim:

The ornamental design for a bicycle carrier for automobiles, as shown and described herein.
